STRUCTURAL SHAPE

Robert J. Harry, Homestead, Pa.

Application May 3, 1930. Serial No. 449,618

3 Claims. (Cl. 189—37)

This invention relates to structural shapes and, while not limited thereto, relates more particularly to structural shapes of the larger sizes and has for one of its objects the provision of beams 5 varying in cross-section throughout their length so as to provide maximum cross-section where the stress is greatest and minimum cross-section where the stress is least.

Another object is to provide a beam structure 10 which will permit the use of the lightest beam for a given load, and to increase the useful load which the beam will support for the same maximum section modulus.

Heretofore beams have generally had a uniform cross-section throughout their entire length, whereas the load supported produces stresses which vary throughout the length of the beam. Uniform section beams are therefore subject to a marked disadvantage as much excess weight must 20 be used on account of the same section being employed where the bending moment is maximum and minimum and also where the shear is maximum and minimum.

In the drawing: 25 Figure 1 is a side elevation of a beam constructed in accordance with this invention.

Figure 2 is a longitudinal section taken on the line II—II of Figure 1.

Figure 3 is an end elevation. 30 Referring more particularly to the drawing, the letter A designates the web portion of the beam and the letter B designates the flange portions.

The web A is composed of a relatively thin 35 center section 2 and successively thicker end sections 3 and 4, all of which sections are welded together end-to-end to form a continuous structure.

The flange portions B are each composed of 40 three rolled metal plates 5, 6 and 7 arranged one on top of the other and welded together along their longitudinal and end edges.

The plates 5 are of the same length as the center section 2 of the web and are welded direct- 45 ly thereto by welds 8 along the longitudinal edges of the web-plate. The web sections 3 are of a greater height than the section 2, the difference being equal to the thickness of the flange plates 5, so that the edge faces of the web-plates or sec- 50 tions 3 are flush with the outer faces of the flange plates 5. The second flange plates 6 are of a length equal to the combined length of the web-plates 2 and 3 and extend along the web-plates or sections 3 and over the flange plates 5 and are 55 welded along the longitudinal edges of the web-

plates or sections 3 by welds 9 and also along the longitudinal and end edges of the flange plates 5, as at 10 and 11, respectively. The web sections 4 are an amount higher than the sections 3 equal to the thickness of the flange plates 5 and 6 so 60 that their edge faces are flush with the outer faces of the flange plates 6. The third and outer flange plates 7 are of a length equal to the combined length of all the web sections 2, 3 and 4 and extend along the whole beam. The flange plates 65 7 are welded along the longitudinal edges of the web sections 4 by weld 12 and along the longitudinal and end edges of the flange plates 6, as at 14 and 15, respectively.

The above construction provides an integrally 70 welded beam having a web and flanges of varying cross-section so as to provide maximum cross-section where the stress is greatest.

The invention is shown in connection only with a shape analogous to an I-beam. But it may be 75 applied to various shapes which are in general similar to I-beams but differ therefrom in the flanges or other laterally projecting portions at the edges of the webs.

The invention is illustrated in connection with 80 arc welding. But it is applicable also to shapes in which the parts are welded together by any one of various other known or suitable methods.

It will be understood that while I have illus- 85 trated one specific embodiment of my invention, I do not wish to be limited thereto since various modifications may be made to accommodate the beam for carrying various loads.

I claim:

1. As a new article of manufacture, the struc- 90 tural shape, characterized by having a cross-sec- tion within the limits that may be rolled as an integral shape, which comprises integral flange and web portions formed of rolled metal plates and continuous line welds uniting the flanges 95 and longitudinal edges of the web portions into a unified structure, said web portion being com- posed of a plurality of relatively short lengths of rolled metal plates of varying thickness welded end-to-end to form a continuous structure of 100 single plate thickness, and said flange portions being of varying thickness so as to provide for the maximum cross-section in said web and flange portions where the stresses are greatest.

2. As a new article of manufacture, the struc- 105 tural shape, characterized by having a cross-sec- tion within the limits that may be rolled as an integral shape, which comprises integral flange and web portions formed of rolled metal plates and continuous line welds uniting the flanges 110

and longitudinal edges of the web portions into a unified structure, said web portion being composed of a plurality of relatively short lengths of rolled metal plates of varying thickness welded end-to-end to form a continuous structure of single plate thickness, and said flange portions being composed of a plurality of plate sections of varying lengths mounted one on top of the other and welded together by continuous line welds along their ends and longitudinal edges to provide flanges of varying cross-sectional area throughout their lengths whereby said beams have a maximum cross-section in their web and flange portions where the stresses are greatest.

15 3. As a new article of manufacture, the structural shape, characterized by having a cross-section within the limits that may be rolled as an integral shape, which comprises integral flange and web portions formed of rolled metal plates

20

and continuous line welds uniting the flanges and longitudinal edges of the web portions into a unified structure, said web portions being composed of a plurality of relatively short lengths of rolled metal plates of successively less thickness 80 toward the transverse center of the beam, said plates being welded end-to-end to form a continuous structure of single plate thickness, and said flange portions being each composed of one continuous rolled metal plate extending along 85 the entire length of said beam, and other plates mounted on the inside face of said first named plate and welded together and to said continuous plate by line welds, said last named plates extending between the joints in said web so as 90 to form a flange increasing in cross-section as the web decreases in cross-section.
